RAIL LIFTER

Raymore D. MacDonald, La Grange, Ill., assignor
to Athey Products Corporation, Chicago, Ill., a
corporation of Illinois

Application May 7, 1949, Serial No. 92,039

6 Claims. (Cl. 254—104)

1

This invention relates to rail lifters, and more particularly to power drawn equipment adapted to use in removing railroad and street car tracks and the like which are secured to ties and/or imbedded in ground or pavement.

One of the objects of my invention is to provide a rail lifter which is supported by wheels and adapted to be drawn by a tractor or the like along the rail being lifted, and having a lifting structure supported between the wheels for raising the rail while the wheels compress the ties and/or turf or pavement adjacent the rail.

As another object, my invention has within its purview the provision of a wheel supported rail lifter adapted to be drawn by a tractor or the like and having a lifting structure including a roller closely above the normal rail level which runs along the under surface of the rail as the lifter is drawn, and there being a tongue structure through which draft force for drawing the lifter is applied directly to the lifting structure at a position for promoting both flexibility and stability of operation.

My invention further comprehends the provision of a rail lifter adapted to use in association with a power driven motivating machine embodying a winch, and which rail lifter includes a tongue structure through which draft force is applied thereto for accomplishing a part of the rail lifting operation and wherein said tongue serves as a support for winch operated equipment adapted to effecting the initial lifting of rails.

It is a further object of this invention to provide a rail lifter adapted to separate motivation and carried by track wheels which cover considerable surface areas on opposite sides of the rail being lifted and which are spaced so as to pass in relatively close proximity to the opposite sides of the rail being lifted.

Other objects and advantages of the invention will be apparent from the following description and the accompanying drawings in which similar characters of reference indicate similar parts throughout the several views.

Referring to the two sheets of drawings,

Fig. 1 is a side elevational view depicting a preferred embodiment of my invention in its adaptation to rail lifting while motivated by a conventional form of tractor indicated in dot and dash lines;

Fig. 2 is a fragmentary side sectional view of a portion of the structure shown in Fig. 1, drawn to a larger scale than Fig. 1, and illustrating certain additional details of the structure in an adaptation to the lifting of a railroad rail or the like;

Fig. 3 is a top plan view of the rail lifter shown in Figs. 1 and 2;

Fig. 4 is a rear end elevational view taken substantially as indicated by a line 4—4 in Fig. 1 and

in the direction indicated by accompanying arrows; and

Fig. 5 is a fragmentary detail of a portion of one part of the apparatus which is illustrated in Fig. 2.

In the exemplary embodiment of my invention which is disclosed in the accompanying drawings for illustrative purposes, I have provided a portable rail lifting unit which is adapted to motivation by separate power equipment, such as a tractor. As shown in Figs. 1 and 2, a preferred embodiment of my track lifter includes a pair of track wheels 10 and 12 in laterally spaced and aligned relationship, which track wheels are connected by a main shaft 13, from which a rail lifting yoke 14 is suspended. Draft force for moving the track lifter is applied through a tongue structure 15, one end of which is secured to and supported by the yoke 14, and the other end of which is provided with a coupling unit 16 through which it is connected to a draw bar 17 of a tractor 18. The tractor illustrated is one of the track laying type and has at the rear end thereof a winch drum 19 which is subject to actuation by the tractor engine for winding a cable 20 thereon. For use with power equipment such as the illustrated tractor having the winch 19 thereon, I have provided a sheave 22 which is supported for rotation at the mid-portion of the tongue structure 15 above the normal level of a rail which is to be lifted, whereby the winch cable 20, when extended over the sheave 22 and provided with a rail gripping element 23, may have lifting force applied therethrough from the winch for initially raising the end of a rail 24 to a level such that a roller 25 carried by the yoke 14 may be placed under the lifted end of the rail by forward movement of the rail lifter unit. With the raised end of a rail passing over the roller 25, the remainder 40 of the rail is lifted from its normally anchored position by forward movement of the rail lifter along the rail, and with the rail gripping element 23 disconnected from the rail, so that the roller 25 passes longitudinally beneath the rail during such movement of the rail lifter. It may be readily appreciated that with the disclosed combination of apparatus, the tractor holds the ties and adjacent turf and pavement in place during the initial lifting movement of the rail and loosening of the spikes, while the rail lifter compresses those elements into their normal positions after the rail has been separated therefrom.

Giving more detailed consideration to the disclosed rail lifter and its illustrative adaptation, it may be understood that while the structure is well suited to the lifting of railroad rails of track installations where the tops of the ties and the rails are exposed above the ground level, the illustrated adaptation shows the ties below the

normal ground level and the tops of the rails practically flush with the level of a turf or pavement, as is usually the case in street car tracks, and the like. As depicted in Figs. 1, 2 and 4, ties 26 normally have rails 24 and 27 secured thereto in spaced relationship by spikes 29. In the present instance, the tops of the rails are practically flush with a surface 30 of adjacent and intervening turf or pavement 32.

Although other types of supporting wheels 10 might be utilized for my track lifter, my preference for the disclosed track wheels 10 and 12 emanates from the fact that such track wheels distribute their loads over large surface areas extending along the rail being lifted. Such track wheels, as illustrated in Fig. 1, each embody a longitudinally extending beam 33 having circular track carrying wheels 34 and 35 journalled for rotation at opposite ends of the beam 33 on shafts 36 and 37 respectively. A track 38 is made up of a series of links 39, which links are so constructed and connected that they follow a path encompassing the ends of the track carrying wheels and bridging the space therebetween. Also, the construction and interconnection of the links is such that they resist flexure between the track carrying wheels and distribute their load over the entire area of contact with the ground.

The main shaft 13, which determines the lateral spacing between the track wheels 10 and 12, has its opposite ends secured to the beams 33 of the track wheels, substantially midway between the ends thereof. Between the beams 33 of the track wheels, a sleeve 40 is journalled for rotation on the main shaft 13. This sleeve 40 has the yoke 14 secured thereto. While the spacing between the track wheels 10 and 12 is sufficient to promote free swinging movement of the yoke 14 therebetween, and the yoke is of sufficient width to receive a rail 24 with room for movement of the rail therethrough, it is my preference that the track wheels should run in relatively close relationship along the opposite sides of the rail being lifted, in order that they will effectively perform their desired compression action upon the ties and turf or pavement near the rails.

The yoke 14, in my disclosed structure, includes pairs of side plates 42 and 43 in opposed and spaced relationship axially of the sleeve 40 which define side arms of the yoke and are separated axially by said sleeve, so as to be disposed on opposite sides of a central plane between the track wheels 10 and 12. At one end, each of the side plates 42 and 43 is secured to the sleeve 40 by welding, as at 44 and 45 respectively; while at their other ends, bearing sleeves 46 and 47 are secured to and extend between the side plates 42 and 43 respectively, by welding as at 48 and 49. These bearing sleeves 46 and 47 support the opposite ends of a cross shaft 50, which cross shaft is secured in place by fastening means, such as spool pins 52 and 53. Between the side arms, the spool type roller 25, having end flanges 55, is journalled for rotation on the cross shaft 50.

From the foregoing description of the structure and supporting parts for the yoke 14, it may be readily understood that this yoke is suspended for swinging movement between the track wheels 10 and 12 from the main shaft 13. Also, as shown in the drawings, the length of the side plates is such that they terminate above, but closely adjacent the lower surfaces of the wheels, so as normally to pass freely above the surface upon which the wheels run. As shown in Figs. 2 and 4, the space between the sleeve 40 and roller 25

is sufficient for free passage of a rail therebetween, so that during movement of the rail lifter along a rail, the roller 25 runs along the lower surface of the rail.

In the disclosed structure, the draft force for moving the rail lifter along the rail is applied through the tongue 15 to the yoke. The tongue 15 includes substantially parallel and longitudinally extending side beams 56 and 57, respectively, having hinge plates 58 and 59 secured to and extending from their rear ends. These hinge plates have coaxial bearing collars 60 and 62 secured thereto and journalled on cross pins 63 and 64 which extend through the side plates 42 and 43 respectively of the yoke. In addition to the hinge plates 58 and 59 being located between the respective side plates 42 and 43, the axis of the pins 63 and 64 is positioned forwardly of the axes of the shafts 13 and 50 and at a position well below the axis of the main shaft 13. Thus, the axis of the pins 63 and 64 is much closer to the axis of the cross shaft 50 than to the axis of the main shaft 13. This position of the axis of the pins 63 and 64 is selected to effect a balance between the draft force necessary to move the rail lifter and the lifting force applied through the roller 25 to the lower surface of a rail being lifted, so as to stabilize operation of the yoke during the forward movement of the lifter. That is, the application of the draft force to the yoke at a position near the axis of the cross shaft 50 permits the uniform movement of the roller 25 along the bottom surface of a rail during forward movement of the rail lifter, and as the lifting force is applied to the rail through the roller 25. On the other hand, the ability of the yoke to swing relative to the main shaft 13 not only facilitates the manipulation of the yoke position during the lifting of a rail to its position upon the roller at the commencement of the lifting operation of a rail section, but the purchase or leverages secured by the relative positions of the shafts 13 and 50 and the axis of the pins 63 and 64 also tends to effect the production of the desired lifting forces with a relatively uniform draft force.

At the mid-portion of the tongue, and forwardly of the track wheels 10 and 12, bearing blocks 65 and 66 are secured to the top surfaces of the tongue side beams 56 and 57 respectively and carry a shaft 67 upon which the sheave 22 is journalled for rotational movement. In utilizing the sheave 22 for effecting the initial lifting and placement of the end of a rail upon the roller 25, I prefer to utilize a rail gripping element, such as 23, on the end of the winch cable 20 which is readily attachable and detachable from the rail, and which will preferably slide along the rail if the rail lifter is moved forwardly or rearwardly during initial lifting and positioning of the roller 25 relative to the end of the rail.

As depicted in Figs. 2 and 5, the rail lifting element 23 includes a pair of oppositely disposed tongs 68 and 69 connected for relative rotational movement by a pin 70. Integral arms 72 and 73 on the opposite sides of the pin 70 from the tongs 68 and 69 respectively provide levers for effecting the actuation of the tongs toward and from one another. In addition, links 74 and 75 are pivotally connected to the extending ends of the arms 72 and 73, as well as being pivotally connected together and to a cable connector 76, so that the tongs are normally spread apart when the tension on the cable is released and are forced

into gripping relationship against the chain when tension is applied through the cable 20.

At their forward ends, the side beams 56 and 57 of the tongue are secured together by an end plate 77, as well as by upper and lower end plates 78 and 79. The plates 77, 78 and 79 have secured thereto a sleeve 80 which extends longitudinally of the forward end of the tongue and carries a coupling bar 82 having a yoke 83 at its forward end and forming a part of the coupling unit 15. In the disclosed structure, a clevis block 84 is secured to the yoke 83 on the coupling bar 82 by a cross pin 85; the clevis block 84 being adapted to removable attachment to the tractor draw bar by a coupling pin 87.

From the foregoing description and reference to the accompanying drawings, it may be readily understood that I have provided a rail lifter adapted to motivation by separate power equipment, such as a tractor, and which is capable of the rapid and effective removal of railroad rails from their holding ties by the movement of the lifter along the rail, while holding the ties and the adjacent turf or pavement in place. This rail lifter embodies a further provision for the initial lifting and placement of a rail prior to its complete removal, as aforementioned. Furthermore, the rail lifter structure itself is constructed and arranged to permit smoothness and effectiveness of operation as well as the ease of starting the operation on a new rail.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A rail lifter adapted to motivation by separate power equipment for removing rails from ties and the like and comprising, in combination, a pair of axially aligned track wheels, each of which embodies a longitudinal beam and track supporting wheels at opposite ends of the beam, a shaft extending between and supported by the mid-portions of the beams, a rail lifting yoke suspended for swinging movement from the shaft between the track wheels, said yoke including opposed and separated side supports joined at their lower ends by a cross shaft, said cross shaft having a roller journalled thereon for running beneath the raised end of a rail as the lifter is moved therealong, and a tongue structure connected to the yoke and projecting beyond the track wheels for applying draft force to the lifter from said power equipment.

2. A rail lifter for removing track rails from ties or the like and comprising, in combination a movable supporting structure, a yoke suspended from the movable supporting structure for swinging movement relative thereto in a plane substantially parallel to the normal direction of movement of the supporting structure, said yoke including a cross member below the axis of swinging movement for passage beneath the rail during movement of the supporting structure.

3. A rail lifter as defined in claim 2, and further characterized by a tongue structure connected to the yoke and through which force is applied for effecting movement of the supporting structure along a rail.

4. A rail lifter adapted to motivation by separate power equipment for removing rails from ties and the like and comprising, in combination, a pair of axially aligned track wheels, each of which embodies a longitudinal beam and track supporting wheels at opposite ends of the beam, a shaft extending between and supported by the mid-portions of the beams, a rail lifting yoke suspended from the shaft between the track wheels, said yoke including opposed and separated side supports joined at their lower ends by a cross shaft, said cross shaft having a roller journalled thereon for running beneath the raised end of a rail as the lifter is moved therealong, and a tongue structure connected to the yoke and projecting beyond the track wheels for applying draft force to the lifter from said power equipment and said tongue structure being connected to the yoke at a position closer to said cross shaft than to the first mentioned shaft.

5. A rail lifter adapted to motivation by separate power equipment having a winch and a cable connected thereto, for removing rails from ties and the like and comprising, in combination, a pair of axially aligned track wheels, each of which embodies a longitudinal beam and track supporting wheels at opposite ends of the beam, a shaft extending between and supported by the mid-portions of the beams, a rail lifting yoke suspended from the shaft between the track wheels, said yoke including opposed and separated side supports joined at their lower ends by a cross shaft, said cross shaft having a roller journalled thereon for running beneath the raised end of a rail as the lifter is moved therealong, and a tongue structure connected to the yoke and projecting beyond the track wheels for applying draft force to the lifter from said power equipment, said tongue structure rotatably supporting a cable pulley at the mid-portion thereof and at a level above the cross shaft to serve with said winch cable in lifting a rail onto the cross shaft.

6. A rail lifter adapted to motivation by separate power equipment having a winch and cable thereon for removing rails from ties and the like and comprising, in combination, a pair of axially aligned wheels, a main shaft extending between and supported by the wheels, a rail lifting yoke suspended from said main shaft between the wheels, said yoke including opposed and separated side supports joined by a cross shaft at a position spaced below the main shaft a distance such that the raised end of a rail will pass between the main shaft and the cross shaft and over the cross shaft as the lifter is moved along the rail, and a tongue structure projecting from the yoke and beyond the wheels for applying draft force to the lifter, said tongue structure including spaced side beams, and having a sheave journalled for rotation between the side beams so that the winch cable may be extended over the sheave and secured to the rail for providing purchase to lift the rail for effecting the initial placement of the rail upon the cross shaft.
